CLAIM

The ornamental design for a mobile terminal display screen with an animated graphical user interface, as shown and described.

DESCRIPTION

FIG. 1 is a front view of a first image of a first embodiment of a mobile terminal display screen with an animated graphical user interface;

FIG. 2 is a front view of a second image thereof, the mobile terminal is omitted for ease of illustration;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a first image of a second embodiment thereof;

FIG. 8 is a front view of a second image thereof, the mobile terminal is omitted for ease of illustration;

FIG. 9 is a front view of a third image thereof;

FIG. 10 is a front view of a fourth image thereof;

FIG. 11 is a front view of a fifth image thereof;

FIG. 12 is a front view of a sixth image thereof;

FIG. 13 is a front view of a first image of third embodiment thereof;

FIG. 14 is a front view of a second image thereof, the mobile terminal being omitted for ease of illustration;

FIG. 15 is a front view of a third image thereof;

FIG. 16 is a front view of a fourth image thereof;

FIG. 17 is a front view of a fifth image thereof; and,

FIG. 18 is a front view of a sixth image thereof.

The appearance of the image transitions sequentially between the images shown in FIGS. 1-6, 7-12, and 13-18, respectively. The process or period in which one image transitions to another forms no part of the claimed design. The dashed line showing of a mobile terminal in FIGS. 1, 7 and 13 forms no part of the claimed design. The long dash-short dash lines showing of a display screen in all views forms no part of the claimed design.
